UNITED STATES PATENT OFFICE.

HAROLD E. ROBERTS, OF OVERBROOK, PENNSYLVANIA.

CLOSURE FOR COLLAPSIBLE TUBES AND OTHER RECEPTACLES.

Application filed September 10, 1924. Serial No. 736,859.

To all whom it may concern:

Be it known that I, HAROLD E. ROBERTS, a citizen of the United States, and a resident of Overbrook, county of Philadelphia, 5 and State of Pennsylvania, have invented certain new and useful Improvements in Closures for Collapsible Tubes and Other Receptacles, of which the following is a specification, reference being had to the accompanying drawing.

The present invention is particularly applicable to collapsible tubes such as are used to hold and dispense tooth paste, shaving cream and the like although it may be applied with equal facility to other forms of receptacles, a principal object of the invention being to provide a closure device for such tubes or receptacles which embodies novel features of construction and arrangement whereby the closure can be removed or cleared from the discharge orifice by a simple movement of the thumb or finger and as readily closed over the orifice thus eliminating the tedious and troublesome screwing and unscrewing of the usual cap.

A further object of the invention is to provide a closure device embodying means whereby the closing element may be readily and closely seated over the discharge orifice so as to entirely prevent discharge or leakage of the contents of the receptacle therefrom and in which the closure element may be removed from the orifice when desired to a position apart therefrom and in which it is entirely out of the way of the contents being discharged through the orifice.

Further objects of the invention are to provide a closure device so constructed that the closing element is always maintained in attached relation to the other parts of the device so that it cannot be lost or mislaid, and to provide a closure device which can be both opened and closed by one hand, thereby leaving the other hand of the operator entirely free for any other purpose, for example, for holding a toothbrush on which tooth paste is to be applied from the receptacle of which the closure forms a part.

Still further objects of the invention are to provide a closure of the character aforesaid which readily lends itself to employment with collapsible tubes and other receptacles of which the closure forms a component or integral part or which may be arranged in association with a stopper or plug adapted for insertion in the neck of a bottle

or the like; which is simple in form and construction, not liable to get out of order, may be operated as frequently to open and close the orifice as desired and may be manufactured at a relatively low cost.

Additionally, my invention includes other objects and various novel features of construction and arrangement to which reference may be hereinafter made or which will be apparent from the accompanying drawing in which I have illustrated certain embodiments of the invention.

Referring now more particularly to the said drawing, in Figs. 1 to 4 inclusive I have illustrated one form of my invention in association with a collapsible tube, Fig. 1 being a perspective view of the closure and a portion of the tube with the closing element or cap in position over the discharge orifice. Fig. 2 is a side elevation of the device shown in Fig. 1 with the parts in a similar position; Fig. 3 is a similar side elevation but with certain of the parts shown in a different position and Fig. 4 is a top plan view of Fig. 2. In Fig. 5 I have shown one of my improved closures in association with a cork or stopper adapted for insertion in the neck of a bottle or other receptacle as hereinafter more fully explained. Like numerals are used to designate the same parts in the several figures.

The embodiment of the invention shown in Figs. 1 to 4 inclusive comprises a head 1 conveniently centrally disposed on the end 2 of a collapsible tube 3, the head preferably being formed integral with the tube in any suitable way although, if desired, the head may be formed separately from the tube and secured thereto by soldering or the like, and as the tube itself may be of the usual well known form further description thereof is unnecessary. The head is provided with a substantially centrally disposed discharge passage 4 the lower end of which communicates with the interior of the tube through an opening in the end 2 from which point the passage may extend axially upward for about one-half the vertical height of the head and be thence directed angularly to terminate in a discharge orifice 4' at a suitable point on the surface of the head.

The latter is of somewhat peculiar conformation being preferably plane or substantially plane on its side faces 5, 5 which are arranged parallel to each other and disposed in vertical planes when the head

is held in upright position, while the surface of the head between its side faces is flat in the transverse direction, but when viewed in profile as in Figs. 2 and 3 presents a plurality of areas or surfaces extending in different directions but merging one into the other and which, considering said figures, may be described as follows: Beginning at the base of the head at the left hand side when viewed as in these figures, a short vertically extending surface 6 may first be presented, at the upper extremity of which is an angularly outwardly directed overhanging surface 7 preferably bulged or slightly curved outwardly as best seen in Fig. 2. At the upper extremity of this surface the head may be slightly rounded upwardly as at 7' to merge into a flat surface 8 surrounding the orifice 4' and extending upwardly and inwardly toward the axis of the head for a suitable distance, this surface being preferably disposed substantially at right angles to the overhanging surface 7. At its upper extremity the surface 8 merges into a rounded surface 9 extending downwardly and in a direction generally away from the surface 8 and which in turn merges into a generally vertically extending surface 10 at the lower end of which the head is curved outwardly and then inwardly to form a surface 11 which in effect forms a cam for a purpose to be hereinafter described and which for convenience will be referred to as such. At the inner and lower end of the cam a short substantially vertically extending surface 12 may be provided to extend from the cam to the base of the head, this surface corresponding more or less to the surface 6 at the opposite side of the head.

For closing the orifice 4' so as to prevent the escape of the contents of the tube therethrough, a closing element is provided which may conveniently be in the form of a cap or button 14 having a flat or substantially flat under surface of sufficient diameter to span the orifice and extend somewhat beyond the edges thereof when positioned thereover and preferably rounded on its outer surface, the cap being thus substantially in the form of a segment of a sphere, while for supporting the cap and controlling its position a bail, conveniently formed of wire, is provided, this bail being of generally U-shaped form and of sufficient width between its legs or arms 15 to seat more or less snugly over the body with the legs lying parallel to the sides 5—5 thereof as shown in Fig. 4, the free ends of the bail being respectively turned inwardly and terminating in suitable bores formed in the cap. At its opposite extremity and preferably centrally of its transverse portion 15' the bail is provided with an out-

wardly directed loop 15" forming a tab or projection adapted for convenient engagement by the finger of the operator.

Means are provided for holding the bail in assembled relation with the head and, additionally, for forming a fulcrum about which the bail may be moved, said means conveniently comprising a pair of pins 16 extending horizontally outward from each of the sides 5 of the head, the pins of each pair being respectively positioned above and below the adjacent leg of the bail and spaced sufficiently far apart vertically to permit the bail to be freely moved between them.

It will be understood that the length of the bail is so proportioned with respect to the head that when the cap is seated over the orifice 4' the transversely extending part 15' of the bail may be sprung downwardly, by suitable pressure on the tab 15", over the high point of the cam 11 so as to engage and be retained beneath the undercut portion of the cam thus holding the cap firmly in position over the orifice, the inherent resiliency of the wire of which the bail is formed being ordinarily sufficient for this purpose. In certain instances, however, it may be desirable to provide a resilient gasket 17 and secure the same on the surface 8 about the mouth of the orifice 4 and also to provide the under face of the cap with a disk 18 of similar resilient material; under such circumstances when the bail is forced over the high point of the cam 11 the disk and gasket, or either of them if but one be employed, are more or less compressed, thus assisting in permitting the passage of the bail over the high point of the cam. Furthermore after the bail is engaged beneath the cam the gasket and disk continue to remain in somewhat compressed condition thereby positively preventing any leakage between the cap and surface 8.

When it is desired to dispense the contents of the tube or other receptacle to which my improved closure is attached, it is only necessary to push upwardly with the finger or thumb on the tab 15", assuming the parts to be in the position shown in Fig. 2, which results in moving the cap downwardly along the surface 8, the bail meanwhile fulcruming and sliding longitudinally to some extent between the pins 16, and thence over the curved portion 7' to finally seat against the surface 7, coaction of the transverse portion 15' of the bail with the curved surface 9 acting to draw the cap snugly against said surface and maintain the position of the parts shown in Fig. 3 so long as may be desired. It will be observed that when in this position the cap is entirely free and clear of the surface 8 and orifice 4' thus preventing any of the contents of the tube or other receptacle from coming in contact with the cap or bail as the same passes from the

orifice. It will of course be obvious that the cap may be as readily closed over the orifice when desired by moving the tab 15" in reverse direction so as to raise the cap over the rounded surface 7' and from thence move it over the orifice against which it can be firmly clamped by forcing the bail over the high point of the cam 11 in the manner already described.

10 It will be noted by reason of the peculiar conformation of the surface of the head that the bail, when being moved from closed to open position, is capable of a suitable longitudinal movement sufficient to permit the cap to ride over the curved surface 7', this movement taking place while the transverse portion of the bail is traveling upwardly from the high point of the cam 11 and over the surface 10, and further, that 15 the relative disposition of the curved or auxiliary cam surface 9 and the undercut surface 7 is such that the cap may be secured against the latter by urging the bail upwardly over the auxiliary cam surface until 20 it attains suitable frictional contact therewith.

As hitherto stated, the use of my improved closure is in no way confined to collapsible tubes or containers of like nature although 30 it conveniently lends itself to such employment. Thus, for example as shown in Fig. 5, the closure may be arranged in association with a stopper S having an internal passage S' communicating with the passage 4 in the closure head, the stopper being adapted for insertion in a bottle or the like so that instead of having to remove and replace the stopper each time that it be desired to pour out some of the contents of the bottle, the 35 stopper may be permanently inserted therein and the closure operated to open and close the orifice 4' whenever it be desired to withdraw a portion of the contents.

While I have herein illustrated and described certain embodiments of my invention with considerable particularity, I do not thereby desire or intend to limit myself to any precise details of construction and arrangement of the various elements of the 45 device nor to the employment of my improved closure in connection with receptacles of any particular form, the invention being capable of utilization in numerous other industrial applications than those to which I have referred and the form, construction and arrangement of the various parts being susceptible of modification in minor particulars from the embodiments shown and described without departing from the spirit and scope of the invention as defined in the appended claims.

Having thus described my invention, I claim and desire to protect by Letters Patent of the United States:

1. A closure for a receptacle, comprising

a head having an internal passage extending from its base to its exterior surface and there terminating in a discharge orifice, a cap adapted to seat over said orifice, a bail operative to support the cap, means carried by the head adapted to guide the bail when moved with respect thereto, and means on the head operative to draw said bail longitudinally when the bail is forced thereover to thereby seat the cap snugly against the 75 orifice.

2. A closure for a receptacle, comprising a head having a discharge passage extending therethrough and terminating in a discharge orifice on a surface of the head, a U-shaped bail substantially embracing the head, a cap supported at one end of the bail and adapted to seat over the orifice, and means carried by the head for maintaining the bail in assembled relation therewith and operative 80 to form a fulcrum therefor, said head having a cam surface remote from the surface in which said discharge orifice is disposed and operative when the closed end of the bail is forced thereover to draw said bail longitudinally and thereby seat the cap snugly 85 over the orifice.

3. A closure for a receptacle, comprising a head having a passage extending therethrough and terminating in a discharge orifice in a surface of said body angularly disposed with respect to its longitudinal axis, a bail embracing said head and having a transversely extending part, a cap carried by the bail and adapted to seat over said 90 orifice, means adapted to hold the bail in assembled relation with the head and to form a fulcrum therefor, and separated cam surfaces on the head adapted for cooperation with the transversely extending portion 100 of the bail, whereby when said bail is moved about said fulcrum and over one of said surfaces the cap is drawn snugly over said orifice and when the bail is moved over the other cam surface the cap is drawn against another surface of said head in angular disposition to the surface in which said discharge orifice is located.

4. A closure for a receptacle, comprising a head having a passage extending therethrough and terminating in a discharge orifice in a surface of the head, the sides of the head between which said surface is disposed extending in substantially parallel planes, a bail embracing the head and having legs extending adjacent said sides and a transverse portion extending parallel to said surface, a cap carried by said bail at its end opposite said transverse portion and adapted to seat over said orifice, and means projecting from each of said sides above and below the adjacent leg of the bail operative to hold the bail in assembled relation with the head and to form fulcrums about which said bail may be moved, said head being 115 120 125 130

provided with a cam surface adapted for cooperation with the transverse portion of the bail and of such contour that when the bail is moved thereover the cap is drawn 5 against the surface in which said orifice is disposed.

5. A closure for a receptacle, comprising a head having a passage extending therethrough and terminating in a discharge ori-

10 fice in a surface of the head, the sides of the head between which said surface is disposed extending in substantially parallel planes, a bail embracing the head and having legs extending adjacent said sides and a trans-

15 verse portion extending parallel to said surface, a cap carried by said bail at its end opposite said transverse portion and adapted to seat over said orifice, and means project- ing from each of said sides above and be-

20 low the adjacent leg of the bail operative to hold the bail in assembled relation with the head and to form fulcrums about which said bail may be moved, said head being pro- vided with separated cam surfaces each

25 adapted for coaction with the transverse portion of the bail and of such contour that when the bail is moved over one of said surfaces the cap is drawn snugly over said orifice and when moved over the other of 30 said surfaces the cap is drawn against another surface of said head in angular dispo- sition to the surface in which said orifice is disposed.

6. A closure for a receptacle, comprising 35 a head having an internal passage terminat- ing in a discharge opening in an end sur- face of the head, the sides of the head ex- tending in transversely spaced parallel planes, a substantially U-shaped bail em- 40 bracing the head and having legs respective- ly extending adjacent each of said sides and a transverse portion provided with a finger tab, a cap carried by the bail at its end oppo- site said transverse portion and adapted to 45 seat over and close said orifice, a pair of spaced pins extending from each side of the head on opposite sides of the adjacent leg of the bail and forming guiding and ful- cruming means therefor, and separated cam

surfaces on the head adapted for coaction 50 with the transverse portion of the bail and respectively of such contour that when the bail is moved over one of said surfaces the cap is drawn against and seated over said orifice and when moved over the other sur- face the cap is drawn against a surface of 55 the head remote from that in which said orifice is disposed.

7. A closure for a receptacle, comprising 60 a head having parallel spaced sides and an internal passage terminating in a discharge orifice in an end surface of the head between said sides, a wire bail embracing the head and having a leg disposed adjacent each side thereof and a transverse portion, a cap sup- ported by the bail remote from the trans- 65 verse portion and adapted to seat over the orifice, spaced projections extending from each side of the head on opposite sides of the adjacent leg of the bail and forming 70 guiding and fulcruming means therefor, and spaced cam surfaces on the head cooperative with the transverse portion of the bail to draw the cap against different points on the head when the bail is moved thereover. 75

8. A closure for a receptacle, comprising 80 a head having parallel spaced sides and an internal passage terminating in a discharge orifice in an end surface of the body between said sides, a wire bail embracing the head and having a leg disposed adjacent each side thereof and a transverse portion, a cap sup- ported by the bail remote from the trans- 85 verse portion and adapted to seat over the orifice, spaced projections extending from each side of the head on opposite sides of the adjacent leg of the bail and forming guiding and fulcruming means therefor, spaced cam surfaces on the head cooperative with the transverse portion of the bail to draw 90 the cap against different points on the head when the bail is moved thereover, and a resilient gasket adapted for interposition be- 95 tween the cap and the surface in which the orifice is disposed.

In witness whereof, I have hereunto set my hand this 6th day of September, 1924.

HAROLD E. ROBERTS.
